A. L. Simonsen

Inventor
D. W. Thomas

United States Patent Office.

DANIEL W. THOMAS, OF NEW YORK, N. Y., ASSIGNOR TO HENRY BREWSTER, JOHN W. BUTTON, AND JAMES LAWRENCE, OF SAME PLACE.

Design No. 4,323, dated August 30, 1870.

DESIGN FOR A CARRIAGE-DOOR HANDLE.

The Schedule referred to in these Letters Patent and making part of the same.

To all whom it may concern:

Be it known that I, DANIEL W. THOMAS, of the city of New York, in the county of New York and State of New York, have invented, originated, and designed a new Pattern for Carriage-door Handles, of which the following is a full, clear, and exact description, reference being had to the accompanying drawing making part of this specification.

My invention consists of a novel design for carriage-door handles.

In the accompanying drawing—

Figure 1 is an end view of my new design.

Figure 2 is a side view of the same.

The handle proper consists of a central boss, C, carrying two short arms, D D, with oblique ends, as seen in the drawing.

The end view of boss presents an oval, as shown in fig. 1.

What I claim as my invention, and desire to secure by Letters Patent, is—

The design for carriage-door handles, substantially as herein set forth.

D. W. THOMAS.
